MOISTURE EJECTOR VALVE AND SYSTEM

Carl O. Bruestle, Rahway, N. J.

Application February 27, 1948, Serial No. 11,733

5 Claims. (Cl. 303—88)

1

This invention relates to a valve and a system employing it by means of which the moisture (condensate) which collects in compressed air systems is ejected therefrom each time the system is operated.

An object of this invention is to provide a novel form of moisture ejector valve which is self-cleaning, reliable in operation, has a minimum tendency to freeze, is simple in construction and inexpensive to manufacture and maintain, insures against loss of reservoir pressure should the valve become defective and is automatic in operation.

Another object of the invention is to provide a pressure fluid system and particularly a compressed air system incorporating the valve of this invention in such manner that each time a pressure fluid operated device forming part of the system is actuated any accumulated moisture in the system and particularly in the reservoir is automatically ejected.

Other and more detailed objects of the invention will be apparent from the following description of the embodiments thereof illustrated in the attached drawings.

This invention resides substantially in the combination, construction and relative location of parts all as will be hereinafter described.

In the accompanying drawings—

Figure 1 is a longitudinal vertical central cross sectional view through one form of moisture ejector valve in accordance with this invention showing the valve in an unactuated position;

Figure 2 is a similar view showing the valve actuated;

Figure 3 is a cross sectional view taken on the line 3—3 of Figure 1;

Figure 4 is a cross sectional view taken on the line 4—4 of Figure 1;

Figure 5 is a diagrammatic and schematic illustration of a system employing this valve;

Figure 6 is a longitudinal central vertical cross sectional view through a modified form of valve showing it actuated;

Figure 7 is a cross sectional view taken on the line 7—7 of Figure 6; and

Figure 8 is a cross sectional view taken on the line 8—8 of Figure 6.

It is well understood in the art of compressed air systems such as are used on vehicles as, for example, buses, streetcars, and railway cars, both surface and subway, that provision must be made for the ejection from the system of moisture (condensate) which collects therein. In

2

accordance with this invention moisture ejection is effected each time the system is actuated.

The valve of Figures 1 to 4, inclusive, includes a main one-piece housing 1 having a central passage therethrough, and internal threads at the ends as shown. This housing is provided with an apertured internally threaded boss 2 and an internal annular formation 11 of reduced diameter forming a restricted passageway which, as illustrated, consists of an initial portion of fixed radius in the direction of air flow and a terminal portion of gradually increasing radius to form a flaring throat. Threadedly secured in the righthand end of the housing 1 is a bushing 3 forming a fluid tight seal therewith in cooperation with the gasket 4. The bushing 3 has a passage therethrough of two sections of different diameter. The passage 5 is internally threaded as shown and the remainder thereof formed by the sleeve 6. Part 6 is of fixed radius to form a cylinder for the piston 13.

Threadedly mounted in the other end of the housing 1 is a bushing 7 having an exhaust port 9 and forming a fluid tight seal with the housing 1 by cooperation with the gasket 8. The sleeve portion 10 of the bushing is of fixed radius and forms a cylinder for the guide 17 which is not of circular cross section in view of the flat sides 17' formed thereon.

A piston rod 12 is formed on one end of the annularly grooved piston 13 in which is mounted an O-seal ring 14. Intermediate the ends of the piston rod 12 is mounted a second annularly grooved piston 15 in which is mounted the O-seal ring 16. The lefthand end of the piston rod 12 is provided with a wedge-shaped terminal end 18. Interposed between the head end of the bushing 7 and the non-circular guide 17 is a compression spring 19.

The complete valve is diagrammatically illustrated in Figure 5 by the reference character EV. The threaded port in the boss 2 is connected to the sump S of the reservoir R by means of a pipe 20. The reservoir R comprises the storage tank for the compressed fluid, usually air, which is compressed and delivered thereto by means of a power driven compressor (not shown) as is well known in the art. The main compressed air supply connection from the reservoir R is provided by the pipe 21 which is connected to any suitable form of manual or power actuated valve V through a pressure reducing or regulating device PR. The valve V is illustrated as of the manual type and there is provided the actuating handle H. This valve is also provided with the

exhaust connection E and a pressure fluid supply pipe 23 which connects to one or more pressure fluid actuated devices to be controlled by the valve V as, for example, the brake cylinder BC.

It is assumed that the valve V is shown in Figure 5 in unactuated or normal position at which time the brake cylinder BC is connected to atmosphere through pipe 23, valve V and exhaust E. Pressure fluid from the reservoir R is supplied at a reduced pressure to the valve V through the regulator PR but the port in the valve supplied by the pipe 21 is sealed off. Pipe 22 is also connected to atmosphere through the exhaust E. Pressure fluid is continuously supplied to the ejector valve EV through the pipe 20 and into the space in that valve between the pistons 13 and 15, the piston 12 and connected parts being in the position shown in Figure 1. Any moisture that may collect in the sump S will drain through the pipe 20 into that space and particularly into the pocket P, see Figure 1, assuming that the valve EV is placed with relation to the reservoir R in the manner illustrated in Figure 5. As will be apparent, however, this physical relationship need not exist because the moisture will be driven from the sump S to and through the valve EV to atmosphere when the device is actuated by the movement of air along the same path as will now be described.

When the handle H of valve V is actuated to connect pipe 21 to pipe 23 and thus operate the brakes by the supply of pressure fluid to the brake cylinder, air will also be delivered from valve V through the pipe 22 to the righthand face of piston 13. This air will be supplied at a pressure lower than that in the reservoir but the piston assembly will move to the position shown in Figure 2 because pistons 13 and 15 have the same area and therefore the higher pressure from the reservoir from the pipe 20, although acting on these pistons, will be balanced. Therefore, the supply of air at lower pressure to the righthand face of piston 13 will cause the piston rod and connected parts to move from the position shown in Figure 1 to the position shown in Figure 2. For a period of this movement the piston 15 will have moved out of sealing relation with a portion of the internal annular ring 11 so that air may pass through the flaring throat formed thereby and around the piston 15 until it moves into sealing engagement with the cylinder formed by the sleeve 10. As the air in the reservoir R is at a relatively high pressure the escaping air will follow this path at high enough velocity to carry with it any moisture which has accumulated in the sump S, the pipe 20 and the pocket P.

This moisture laden air can pass by the non-circular guide 17 and discharge to atmosphere through the port 9. However, as soon as the piston 15 moves into the cylinder or sleeve 10 the escape of air through the port 9 will be cut off. The piston assembly will remain in the position shown in Figure 2 as long as the brakes or other pressure fluid actuated device are supplied with compressed air. As soon as the handle H of valve V returns to the normal position shown in Figure 5 the supply of pressure fluid through the pipe 21 is cut off, the cylinder of the brake is connected to exhaust and the cylinder for piston 13 is connected to exhaust so that spring 19 which was previously compressed can return the valve piston assembly to the position shown in Figure 1. During the intermediate transient position of the piston assembly on its return stroke, a quantity

of air will again be exhausted to atmosphere through the port 9. Thus, every time the valve EV is actuated in either direction any moisture which has accumulated in the reservoir R, sump S and pocket P of valve EV will be ejected.

The modification of Figures 6, 7 and 8 which can be substituted for that illustrated in Figure 5 has several additional structural features and advantages. In this case the valve body 101 is provided with a longer integral boss 102 and the passage defined by the boss is closed at the lower end but provided with a series of ports 143 opening into the pocket P. The bushing 103 is sealed in the housing by a gasket 104 and receives the pipe 22 as before. The piston 113 which moves in the cylinder formed by the sleeve 106 is provided in this case with a pair of annular grooves in one of which is mounted the O-seal ring 114 and in the other of which is mounted the felt ring 114'.

Threadedly mounted and sealed in the other end of the housing 101 is a bushing 107 which in this case has a somewhat more elongated form than that illustrated in Figure 1 sealed with the housing by means of the gasket 108. The sleeve portion 110 as before forms a cylinder into which the annularly grooved piston 115 with its O-seal ring 116 may move as before. The piston rod 112 unites the pistons 113 and 115 and is provided with a non-circular guide 117 formed by the flats 117' as before. The extending end 118 of the piston rod in this case is provided with a conical, circular seating end 118' for cooperation with a similarly shaped seat 107' formed around the exhaust aperture 109.

On the extended boss 102 is threadedly mounted an apertured bushing 149 forming a seal with the boss 102 by cooperation with the gasket 141. The bushing 149 receives the pipe 20 at one end and is provided with a conical seat 142 at the other end with which cooperates a ball valve 144 biased to seating position by means of the spring 145. The valve housing 101 is provided with the internal annular ring 111 as before which in this case forms a passage consisting of a short converging portion, a portion of fixed radius and a portion of increasing radius, all in the direction of air flow.

The operation of this valve is generally similar to the one previously described. The felt ring 114' is saturated with oil, keeping the cylinder wall in the bushing 103 lubricated, thereby increasing the life of the O-seal ring 116.

In view of the fact that solid particles may accumulate in the system and from time to time be ejected through this valve, they are liable to become lodged in such a position or so damage the O-seal ring 116 as to let air escape around the piston 115 to atmosphere, assuming the conical end 118' of the piston assembly is not in sealing engagement with the seat 107'. Under these conditions, the pressure fluid in the reservoir will slowly leak through the line 20 around the ball check valve 144 until the pressure in the reservoir has fallen to a value where spring 145 is strong enough to reseat the check valve. This spring can be selected so as to maintain a minimum pressure in the reservoir below which it may not fall by slow leakage due to these conditions. It will be quite apparent that if the check valve is not used, all the air in the reservoir might ultimately leak to atmosphere. Thus, the check valve 144 is provided to hold a predetermined minimum pressure in the reservoir. Those skilled in the art will understand

that the check valve need not be incorporated in the valve body 101 but could be a separate check valve connected in the line 20.

In the event that spring 119 should fail for any reason, it is apparent that the piston assembly of the valve would not be returned to normal position corresponding to the position of the valve as illustrated in Figure 1. It would more likely remain in the position shown in Figure 6 in which case the port 109 would be closed by the valve comprising the seat 107' and the conical end 118' of the extension 118 of the piston rod. Thus, the full reservoir pressure would be maintained should this valve fail to operate for any reason including spring fatigue. This cooperation also serves as a stop for the valve piston assembly in normal operation.

It will of course be understood that the ejector valve will operate to remove moisture from the system in the same way as the valve of Figure 1 for actuation in either direction and further description in this respect is not necessary.

From the above description it will be apparent to those skilled in the art that the details comprising the invention herein disclosed are capable of some modification and I do not therefore desire to be limited to the illustrated embodiments but only as required by the claims.

What is claimed is:

1. An ejector valve comprising a body assembly providing two spaced cylinders, the first exhausting to atmosphere and the other provided with a fluid pressure supply and exhaust connection, said body assembly having an internal annular formation providing an annular seat between said cylinders, a pair of spaced connected

pistons, a spring normally holding said pistons so that one is on said seat and the other is at the end of the cylinder having said connection and means for supplying a pressure fluid to the space between said pistons, said pistons at said annular seat cooperating with said second cylinder to prevent the exhaust of pressure fluids through said exhaust port when said valve is actuated.

2. In the combination of claim 1, means attached to said piston for also closing said exhaust port when said valve is actuated.

3. In the combination of claim 1, said means for supplying pressure fluid to the space between said pistons including a normally closed check valve urged to open position for movement of air into said space.

4. In the combination of claim 1, said pistons having peripheral grooves and O-seal rings mounted therein.

5. In the combination of claim 1, the first of said pistons having a pair of peripheral grooves and the second one a single peripheral groove, a lubricating ring in one of the grooves of said pair and an O-seal ring in the other two grooves.
